UNITED STATES PATENT OFFICE.

ANDREW J. WOODMAN, OF INDIAN ORCHARD, MASSACHUSETTS.

IMPROVEMENT IN LET-OFF MECHANISMS.

Specification forming part of Letters Patent No. 129,915, dated July 30, 1872.

To all persons to whom these presents may come:

Be it known that I, ANDREW J. WOODMAN, of Indian Orchard, of the county of Hampden and State of Massachusetts, have invented a new and useful Improvement in Looms for Weaving; and do hereby declare the same to be fully described in the following specification and represented in the accompanying drawing, of which—

Figure 1 is an end elevation, and Fig. 2 a front view of a loom-frame with my invention applied thereto, and the let-off or delivery mechanism of the yarn-beam. Fig. 3 is a horizontal section taken through the ratchet-wheel of the said delivery mechanism.

On November 14, 1871, Letters Patent No. 120,843, for an improvement in the let-off mechanism for looms, were granted to me.

In carrying out my present invention I have combined an arm or lifter and a gravitating cammed lever with the filling "stop-motion" or mechanism, or its long shaft and the draw-pawl of the warp-delivery mechanism, the latter being such as shown in the said patent; the object of my present invention being to estop the delivery of the warp during the period when the lay, through momentum generated in it, may be in movement, after the filling stop-motion may have been put in operation, in consequence of such breakage of the filling-thread or exhaustion of it. By thus estopping the delivery of warp such warp does not become slackened during the false beats of the lay, but maintains its proper tension, and what weavers term "loose cloth" is prevented from being woven.

The drawing represents the warp "let-off" or delivery mechanism, of which A is the worm-shaft; B, the ratchet-wheel thereof; C, the worm; D, the draw-pawl; and E its operative lever; I being the stud or actuator of the said lever, it being extended from the sword a' of the lay L. The said draw-pawl is provided with a hook, a, is disposed between the ratchet-wheel and the loom-frame M, and furnished with a bend or cam, as shown at b. The draw-pawl extends through a staple or slotted plate, F, projected from the loom-frame, the pawl being to slide through or in the slot c of such staple or plate. On the top of the shaft A there is fixed a hand-wheel, d. By taking hold of such wheel and revolving it in one di-

rection the draw-pawl will be moved so as to carry its cam b against the front end of the slot c, whereby, by continuance of the motion of the hand-wheel, the draw-pawl will be caused by the cam to be thrown out of engagement with the ratchet-wheel. This enables a person at any time to revolve the yarn-beam in either direction by manual power applied to the hand-wheel, it being frequently desirable to do so for reasons well understood by weavers.

The mechanism thus described is analogous to what is set forth and claimed in my said patent. I have applied to it or the draw-pawl D thereof, and the filling stop-motion or the long shaft N thereof, a lifter-arm, O, and a gravitating cammed lever P, formed and arranged as shown.

Fig. 4 is a top view, Fig. 5 a side elevation, and Fig. 6 a front-end view of the gravitating-lever, the latter figure exhibiting the arrangement of the cam of the lever with the shank of the draw-pawl D.

The gravitating-lever on the end of the loom-frame and pivoted thereto, as shown at O, has at the end of its lower arm an inclined cam, P, the other or upper arm being hooked upon the end of the lifter-arm, and made heavier than the lower arm so as to overbalance and raise it whenever the lifter-arm drops downward. Instead of so constructing the upper arm I sometimes employ a spring to effect the raising of the lower arm.

Should the shuttle-thread or filling break, or become "run out," or be exhausted in the shuttle, what is termed by weavers the "filling stop-motion" will be put in action to effect stoppage of the loom or the casting of the "driving-belt" from the "fast" to the "loose" pulley. The long shaft N and the upright arm R constitute well-known parts of such filling stop-motion, the fork, slide, or carrier of which is usually disposed in front of the said arm R, which is moved back during a rearward movement of the slide. Such a motion of the arm R causes the long shaft N to turn in its bearings and raise the arm or lifter O, whereby the gravitating cammed lever P will be moved on its fulcrum so as to force the cam p down against the draw-pawl in a manner to crowd it away from and retain it out of action upon the ratchet-wheel B, there-

by preventing any delivery of warp during the false play of the lay or that which, after the shipper has been actuated so as to throw the driving-belt upon the loose pulley, is due to the momentum previously generated in the lay.

I herein make no claim to the mechanism for effecting delivery of the warp, nor to the "filling stop-motion," or any part thereof.

What I claim is—

The arm or lifter O and the gravitating cammed lever P, as arranged and combined together, and with the draw-pawl D of the warp let-off or delivery mechanism, and with the long shaft N of the filling stop-motion, all being substantially as described.

ANDREW J. WOODMAN.
